UNITED STATES PATENT OFFICE.

THOMAS R. KENNEDY AND EDWARD J. KING, OF ROCHESTER, NEW YORK,
ASSIGNORS TO COÖPERATIVE FOUNDRY COMPANY, OF SAME PLACE.

DESIGN FOR A STOVE OR RANGE.

SPECIFICATION forming part of Design No. 35,010, dated August 27, 1901.

Application filed July 22, 1901. Serial No. 69,335. Term of patent 7 years.

To all whom it may concern:

Be it known that we, THOMAS R. KENNEDY and EDWARD J. KING, citizens of the United States, residing at Rochester, in the county 5 of Monroe and State of New York, have invented and produced a new and original Design for Stoves or Ranges, of which the following is a specification, reference being had to the accompanying drawing, forming a part 10 thereof.

The drawing is a perspective view of a stove embodying our design.

The leading feature of the design is the shape and ornamentation of the stove as a 15 whole and of the ornamentation of the separate parts thereof.

The design consists of the elements A, indicating the base; B, the body mounted thereon, and C the high shelf or pipe-section 20 mounting the body, together with the various ornamentations upon the several parts, as will be more fully described. The base A embodies the legs *a*, between which is the central ornament *b*, flanked by ornaments terminating in the large scrolls *b'*. The corners 25 of the base are provided with the ornaments *c*, which extend downwardly upon the legs.

The body B of the stove is provided with the forwardly-extending hearth D, having 30 the depending rim *d*, and below this is the ash-pit section E. Over the hearth is the ash-pit door F, having the ornamented front, and above the latter is the door G. The

front of the body is provided with the oven-door H, having a centrally-arranged oval 35 panel *h*, surrounded by a conventional form of scroll-and-leaf ornamentation *h'* in relief. Below the door is the shelf I, ornamented upon its upper surface and having the depending flange *i* at its outer edge. The fire-pot door K is provided with scroll ornamentation, as is also the stove-body beneath the door, as indicated by *k*.

Extending rearwardly from the end of the stove-body is a reservoir-section L, having 45 the heavy scroll-and-leaf ornamentation *l*. The top of the stove is surrounded with a plain overhanging band or flange M.

The high shelf C, surmounting the stove-body, consists of the centrally-rounded portion O, having the conventional scroll-and-leaf ornamentation P across the center, extending at the sides, forming wings *p*, having a curved outline, and from which project small shelves Q. At the top of the section 55 is the shelf R, and arranged above the latter is a panel S, ornamented as shown.

We claim—

The design for a stove substantially as herein shown and described.

THOMAS R. KENNEDY.
EDWARD J. KING.
